UNITED STATES PATENT OFFICE.

JACOB BUFF, OF UNION HILL, NEW JERSEY.

CAROUSEL.

1,219,913.

Specification of Letters Patent. Patented Mar. 20, 1917.

Application filed November 10, 1915. Serial No. 60,717.

To all whom it may concern:

Be it known that I, JACOB BUFF, a citizen of the United States, and resident of Union Hill, in the county of Hudson and State of New Jersey, have invented a new and useful Improvement in Carousels, of which the following is a specification.

This invention relates to that class of apparatus which is designed for the entertainment of children and commonly designated as a carousel, with the object in view of providing such a structure which is simple and light, and may be readily operated by one of the occupants.

Another object is to provide such a structure which may be erected without difficulty in almost any desired place, and without the necessity of making any substantial or especial provision therefor.

A further object is to provide such a structure in which the frame carrying the seats for the occupants may be rotated either clock-wise or anti-clock-wise, so that the seats may be caused to revolve in either direction.

A still further object relates to certain improvements in the form, construction and arrangement of the several parts whereby the foregoing and other objects may be effectively carried out.

A practical embodiment of my invention is represented in the accompanying drawings, in which—

Figure 1 represents a side elevation of the complete apparatus,

Fig. 2 represents a top plan view thereof,

Fig. 3 represents an enlarged detail section taken in the plane of the line A—A of Fig. 2, looking in the direction of the arrows, and

Fig. 4 represents a similar view taken in the plane of the line B—B of Fig. 2 looking in the direction of the arrows.

The apparatus comprises a base plate 1 which may conveniently be composed of metal circular in form and webbed for strength, which base plate is adapted to rest upon and be secured to suitable flooring or the ground, according to the desire of the user.

Through the center of this plate 1 passes a vertically extending rod or tube 2 which is designed to constitute a vertical pivotal support for the rotating frame of the apparatus, and the upper end of which is secured to a ceiling, beam, or other point

of attachment, conventionally represented at 3, by any suitable means, such, for instance, as a lug or nipple 4. This pivotal support 2 may be conveniently composed of ordinary cast iron pipe, of appropriate size.

A sleeve 5 has its lower end threaded into a nipple 6, which is secured by cap screws 6* to the base 1, the said sleeve surrounding the lower portion of the pivotal support 2. The upper end of this sleeve 5 is also threaded into a flanged nipple 7, which serves to support a rest plate 8 fitted upon the pivotal support 2. A large bevel gear 9 is also fitted upon the pivotal support 2 and lies upon the upper surface of the rest plate 8.

Bolts 10 serve to firmly unite the nipple 7, rest plate 8 and bevel gear 9.

The rotating frame comprises arms 11, 12, 13, 14, which radiate at substantially 90° angle to each other from a hub 15. These arms may conveniently be composed of light wooden beams, such as are conventionally known as "two by fours," and be secured in the hub 15 (which is preferably composed of metal, such as cast iron), by suitable bolts 16. On the outer end of the said arms are mounted seats 17, 18, 19, 20.

A hollow thrust bearing 21 is fixed to the under side of the hub 15 by bolts 22, into which bearing is threaded the lower end of a tubular upright 23, which surrounds the pivotal support 2, and thus provides an elongated bearing for the seat carrying frame during its rotation.

The upper end of the tubular upright 23 has a collar 24 screwed thereon, from which collar guys 25 radiate downwardly to the arms 11, 12, 13, 14, in order to form supports for the seats.

The mechanism for rotating the apparatus includes a bevel pinion 26, which meshes with the gear 9 and is fixed against rotation upon a shaft 27. The inner end of the shaft 27 is mounted in a journal 28 located in the hub 15, while the outer end of the said shaft is supported in a bearing 29 carried by the cross brace 30, which extends from the seat 19 to the seat 20. The journal 28 has a cap 31 provided with a stem 32 slidably mounted in the hub 15, while a coil spring 33 surrounds the said stem 32 and abuts the cap 31 and hub 15 so as to normally hold the said cap at the limit

of its downward movement, while permitting a vertical yielding thereof. This arrangement provides a loose or yielding bearing for the shaft 27 at its inner end, thus 5 permitting a slight lateral movement thereof during the swaying of the seat carrying frame incident to its rotation.

The upper end of the shaft 27 has a short crank 34 fitted against rotation thereon, to 10 the outer end of which crank is pivoted a pitman 35 which has its other end pivoted at one end of an operating lever 36, which is fulcrumed at 37 in the cross brace 30 and is provided, at its upper end, with a T-han- 15 dle 38.

In order to guard against undue swaying of the seat carrying frame during its rotation, I secure, to the under side of the hub 15, yokes 39, four in number, in which are 20 mounted rollers 40. These rollers are of such a size that, when the seat carrying frame is perfectly level, they will be slightly spaced from the rest plate 8, as clearly shown in Fig. 4, while, if the seat carrying 25 frame acquires any considerable amount of sway during its movement, or tilts to any considerable degree from the horizontal, one or more of the said rollers 40 will bear upon the rest plate 8 and thus prevent further 30 swaying or tilting of the said frame, as well as relieving undue strain and wear upon the tubular upright 23.

A foot rest 41 may be bolted or otherwise secured to the cross brace 30 for the 35 use of the occupant who is to actuate the rotating mechanism.

The operation of the apparatus will be obvious from the foregoing description, but it may be simply stated that the occupant 40 of the seat 19 may brace his or her feet against the part 41 and reciprocate the lever 36 by means of the handle 38. This movement will serve to rotate the pinion 26, thereby causing the whole frame to ro- 45 ate about the pivotal support 2.

It will be clear that the actuation of the

lever 36 may be started either by a pull or a push so as to rotate the frame in either direction, and that after the frame has been rotated for a while in one direction, it may 50 be stopped and started in the reverse direction; thus serving to counteract any tendency to dizziness which may be sensed by the occupants.

It will be understood that various changes 55 may be resorted to in the form, construction and arrangement of the several parts without departing from the spirit and scope of my invention; hence I do not intend to be limited to the specific details herein 60 shown and described except as they may be set forth in the claims.

What I claim is:—

1. Apparatus of the class described comprising a pivotal support, a seat carrying 65 frame rotatably mounted thereon, mechanism for rotating the frame, a rest plate mounted below said frame, and rollers de- pending from the frame and spaced slightly from the rest plate for limiting the move- 70 ment of the former toward the latter.

2. Apparatus of the class described comprising a pivotal support, a seat carrying frame rotatably mounted thereon, a gear fitted on said support, a shaft loosely jour- 75 naled in said frame to permit lateral move- ment and carrying a pinion meshed with said gear, and mechanism for rotating the shaft.

3. Apparatus of the class described com- 80 prising a pivotal support, a seat carrying frame rotatably mounted thereon, a gear fitted on said support, a pinion meshed with said gear, a shaft engaging said pinion for 85 rotating it, and a bearing for said shaft lo- cated in the frame adjacent said gear and provided with a yielding cap to permit local lateral movement of the shaft.

In testimony that I claim the foregoing as my invention, I have signed my name, this 90 first day of November 1915.

JACOB BUFF.
